UNITED STATES PATENT OFFICE.

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA.

CONDENSER.

Original application filed February 1, 1922, Serial No. 533,288. Divided and this application filed April 10, 1924. Serial No. 705,599.

My invention relates to vapor condensers and more particularly to condensers adapted for use with air ejection apparatus of the multistage, intercooler type, such as is commonly employed in power plants, and it has for an object to provide apparatus of the character designated which shall be composed of standard units of different sizes, assembled to form a complete condenser organization of any desired capacity.

Another object of my invention is to provide condenser organization assembled from units or elements having the same dimensions at connecting ends but of different ratings or capacities, which units are interchangeable and are capable of ready assembly into condenser organizations of various capacities. These and other objects of my invention will appear more fully in the annexed specification, having reference to the accompanying drawing in which Fig. 1 is a longitudinal section through one element of an ejector embodying a condenser constructed in accordance with my invention; Fig. 2 is a transverse section through a two-element inter-condenser, taken on the line II—II of Fig. 1; Fig. 3 is a view in section taken on line III—III of Fig. 2; Fig. 4 is a view similar to Fig. 1, illustrating the application of my invention to the jet type of intercooler, and Fig. 5 is a view partially in elevation, and partially in section on the line V—V of Fig. 4.

My invention contemplates the provision of a condenser assembled from unit elements, consisting generally of a shell member of the same cross-sectional conformation, but differing in length to give varying condensing capacities, standard tube plates and standard water boxes. The condensers herein disclosed are shown employed in connection with multiple stage ejectors constructed on the unit plan and which are herein briefly described.

In Figs. 1, 2 and 3 of the drawings, the ejector mechanism comprises a number of ejector units each consisting of a first stage ejector 10, a second stage ejector 20, and an inter-condenser 15 located between the ejectors 10 and 20. The ejector 10, which is of the well known steam jet type, consists of a

nozzle 11 and a combining tube 12, and is adapted to exhaust air and other gases from a manifold 13 connected by a valve 14 to the main condenser or other apparatus 55 served. Similarly, the ejector 20 consists of a nozzle 21 and a combining tube 22 and is adapted to exhaust air and non-condensable vapors from the inter-condenser 15 in a manner well understood in the art to which 60 my invention relates. The combining tube 12 is connected by a conduit 17 to an inlet 18 of the inter-condenser 15, by means of which the exhaust from the ejector 10 plus the motive steam from the nozzle 11 is introduced into the inter-condenser. The inter-condenser 15 consists of shell sections 19 provided on their upper sides with the inlets 18 and on their lower sides with outlets 23 and drains 24, and is provided with tubes 26 70 through which cooling water is circulated to effect the condensation of steam and vapor therein. The condensate is removed through the drains 24, in any well known manner, to any desired point, assisted by baffles which 75 tend to prevent the efflux of condensate through the outlets 23. Air and other non-condensable fluids are withdrawn from the inter-condenser through the outlets 23 by the ejector 20, which exhausts to a discharge 80 manifold 27, in a manner readily understood. The manifold 27 may be provided with a non-return valve 28, if desired.

The inter-condenser shells sections 19 are constructed in two or more sizes, corresponding to the capacities of the ejectors; an assembly of two sizes being shown in Fig. 2. The sections are similar in construction, being of the same size and conformation in cross-section and are provided at each end 85 with standard flanges 38; the distinction as to size being secured by difference in length. The outside ends of each of the two outside sections of the inter-condenser assembly carry a tube sheet 35 of a size and shape to 90 correspond with the flange 38 of the shells, and which are adapted to be clamped thereagainst. The tube sheets 35 are adapted to carry the tubes 26 which extend throughout the length of the assembled inter-condenser 95 100 and by means of which cooling water is circulated.

One end of the assembly is provided with a water box member 33 having flanges adapted to be bolted or otherwise secured to the standard flanges 38 and to clamp the tube sheet 35 in position. The member 33 together with the tube sheet 35 defines a reversing chamber 37 by means of which counter-flow of the cooling water is effected. The other end of the assembly is provided with a water box member 41, having an integral partition 40, by means of which the tube sheet 35 at that end is clamped in place, and which defines, with the tube sheet 35, a pair of chambers 42 to effect the flow of cooling water to and from the tubes 26. The member 41 is provided with a cooling water inlet 43 and outlet 44 connected in a cooling water circulating system in any well known manner (not shown).

By means of the standard flanges 38, the various sections of the condenser are secured together in the usual manner by bolts (not shown). Each section is provided with the vapor inlet 18 and the outlet 23, which inlet and outlets are of a uniform size and are provided with standard pipe flanges. The drain ports 25 are preferably connected to a sectional drain pipe 45.

As members constituting an element of my condenser organization are constructed of a uniform size and are provided with standard flanges, any member from one element is freely inter-changeable with a similar member from another element. In assembling the elements of a complete organization to form an apparatus of any desired capacity, the elements are placed in position and the flanges 38 of the shell sections are bolted or otherwise secured together in abutting relation. The tube sheets 35 are next installed, carrying between them tubes 26 of a proper length to extend through the several shell sections of the assembled apparatus in series. The water box members 33 and 41 are then placed in position and the various steam or water connections made on each element, the device is then ready for use.

It will be apparent that by carrying a stock of a comparatively few standard parts, including shell sections of different capacities, the manufacturer is enabled to erect quickly and cheaply a complete condenser organization having widely differing commercial capacities. The flexibility of service made possible by my invention thus presents an enormous advantage over the methods now in vogue among manufacturers, which necessitates either the building of individual apparatus to order for each installation, or the carrying in stock of a great variety of condensers of different styles, designs and capacities.

The adaptability of my unit construction may be illustrated in the following example,

using two sizes of units, A and B, having capacities represented by the arbitrarily selected values 1 and 3:

Elements in the organization	Capacity of each element	Total capacity of the organization
A A	1 1	1
B or A A	3 or 1 1 1	2 3
A B	1 3	4
A A B	1 1 3	5
B B	3 3	6
A B B	1 3 3	7

Utilizing unit constructions such as are illustrated above, the manufacturer may upon receipt of an order assemble forthwith a condenser of the desired capacity from standard stock parts.

In Figs. 4 and 5 I have illustrated a modification of my invention in which I provide inter-condenser elements of the jet type. The fluid exhausted from the primary ejector 10 passes through the conduit 17 to the inlet 18 of the inter-condenser 15, where it is subjected to the condensing action of water from the nozzles 59, mounted in the nozzle boxes 58. The nozzle boxes 58 are supplied with cooling water through the pipes 60 from a header 61, connected to any suitable source. The inter-condenser 15 is provided with the baffle plates 56, forming a mixing chamber 57. The non-condensable fluids pass through the outlet 23 to the second stage ejector 20, while the condensate, plus the cooling water, passes out through the drain pipes 24 to a header 62, from which it is removed by any suitable means.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In varying size condensers of the character designated, shell members each having open ends and fluid inlet and outlet ports, standard end closures for the shell members, the parts being so constructed that any number of standard shell members may be assembled between the standard end closures to form condensers of varying capacities, and means common to the shell members for delivering fluid to each shell member and discharging fluid therefrom.

2. In varying size condensers of the character designated, shell members each having open ends and fluid inlet and outlet ports, standard end closures for the shell members,

the parts being so constructed that any number of standard shell members may be assembled between the standard end closures to form condensers of varying capacities, means common to the shell members for delivering fluid to each shell member and discharging fluid therefrom, and means for supplying cooling fluid effective to condense condensable fluid in each of the shell

10 members.

3. In varying size condensers of the character designated, cylindrical shell members having open ends and fluid inlet and outlet ports, standard end closures for the said shell members including tube plates and water boxes, the parts being so constructed that any number of standard shell members may be assembled between the standard end closures to form condensers of varying capacities, means common to the shell members for delivering fluid to each shell member and discharging fluid therefrom, and tubes extending between the tube plates and communicating with the water

25 boxes.

4. A condenser comprising a plurality of cylindrical shell sections having open ends and secured together in end-to-end relation, each of said shell sections having fluid inlet and outlet ports, closures for the remote 30 ends of the assembled shell sections, and means common to the shell members for delivering fluid to each shell member and discharging fluid therefrom.

5. A condenser comprising a plurality of cylindrical shell sections having open ends and secured together in end-to-end relation, each of said shell sections having fluid inlet and outlet ports, closures for the remote 40 ends of the assembled shell sections including tube plates and water boxes, tubes extending between the tube plates and communicating with the water boxes, and means common to the shell members for delivering fluid to each shell member and discharging 45 fluid therefrom.

In testimony whereof, I have hereunto subscribed my name this ninth day of April, 1924.

JOHN H. SMITH.
